UNITED STATES PATENT OFFICE.

PIERRE ZUCCO, OF SAN FRANCISCO, CALIFORNIA.

DAM CONSTRUCTION:

Application filed August 1, 1922, Serial No. 578,871. Renewed December 15, 1925.

To all whom it may concern:

Be it known that I, PIERRE ZUCCO, a citizen of the United States, residing at the city and county of San Francisco and State 5 of California, have invented new and useful Improvements in Dam Construction, of which the following is a specification.

This invention relates to a dam construction.

10 It is the principal object of the present invention to provide a novel structural formation particularly applicable to concrete dam structures whereby maximum strength may be obtained by the use of a minimum 15 amount of material and a cheap and effectual dam may be readily built, said structure being so formed as to make it possible to increase the height or to further reinforce the structure without inconvenience 20 and danger of creating weaknesses in the dam.

The present invention contemplates the building of concrete dams which are formed with a substantially flat pressure wall 25 against which water may be impounded, and which wall is reinforced horizontally by a plurality of relatively short span corrugations or reinforcing ribs formed along the back of the dam and reinforced vertically 30 by buttresses formed integral with the structure and disposed at intervals throughout the length thereof.

The invention is illustrated by way of example in the accompanying drawings, in 35 which—

Fig. 1 is a view in plan showing the dam with which the present invention is concerned, with parts broken away.

Fig. 2 is a view in transverse vertical 40 section and elevation showing the vertical sectional formation and reinforcement of the dam.

Fig. 3 is a partial vertical section on line 3—3, Fig. 2.

45 Fig. 4 is an enlarged plan section of a portion of the dam showing two of the vertical abutments 11 and the horizontal ribs 13 connecting the same.

Referring more particularly to the drawings, 50 indicates the pressure wall of a dam as here shown. A forward surface of this wall when considered horizontally lies in a flat plane although it will be understood that when required the face of the 55 dam may be arched. This is not essential in the present construction, however, as the

buttresses 11 may be so designed as to withstand any predetermined maximum strain.

Reference being had to Fig. 2 of the drawing, it will be seen that the pressure wall 60 is disposed at an angle to the vertical and that its rear face is corrugated as indicated at 12. These corrugations are formed throughout the height of the dam and extending horizontally between the vertical 65 abutments 11. The corrugations are arranged to progressively decrease in depth as they reach the top of the dam while their rib sections 13 are preferably arched horizontally as indicated at 13^a to tie them to 70 the abutments and which portions also vary in radius.

By referring to Fig. 2, it will be seen that the front face of the wall lies along a plane "A", the arches or the corrugations 75 along a plane "B" and the tops of the ribs along a plane "C." It will also be observed that these three planes are at slightly diverging angles to each other, thus causing the wall to be thicker and more strongly 80 reinforced at its foot while gradually becoming thinner and weaker toward the top. The wall will thus be gradually increased in thickness as it reaches the footing of the dam, and the ribs will increase in depth 85 while their horizontal span will decrease. The abutments 11 may be of any desired width and thickness. They are here shown as tapering in an opposite direction from the wall, and their vertical cross section decreased towards the top. It will be evident 90 from the examination of the drawings that the abutments may be enlarged at any time if desired, and the height of the dam increased as indicated by dotted lines in Fig. 95 2.

Transverse reinforcement 15 may also be provided if required. It is also desirable to form inspection runways 16 in the rear of the wall and to form passageways 17 100 therefor through the abutments.

In building the present structure a mould is formed for the corrugations and may be used successively throughout the height of the dam. Another mould is formed for 105 the abutments and it is thus possible to rapidly and economically cast the dam in place.

It will thus be seen that the present invention provides advantages in that a minimum amount of material is used to construct a dam of maximum strength, the dam 110

being so designed as to prevent it from uplifting, and as such can be used in any kind of soil, and being of such a design as to permit its strength to be readily calculated without using any special formula and repairs to be made. In the event that a leak develops in the dam it can be easily located and in fact insurance against leakage is provided as a richer concrete mixture can be used at points of great permeability without increasing the labor or involving any considerable additional expenditure of time.

It will further be noted that the structure here disclosed makes it possible for the reinforcing steel work to be constantly under observation as the dam is being erected.

While I have shown the preferred form of my invention as now known to me, it will be understood that various changes might be made in the combination, construction and arrangement of parts by those skilled in the art, without departing from the spirit of the invention as claimed.

Having thus described my invention, what I claim and desire to secure by Letters Patent is—

1. A concrete dam comprising an angularly disposed pressure wall decreasing in thickness from the bottom to the top, a plurality of buttresses on the rear side of the wall vertically disposed, interspaced and integral with the pressure wall, and a plurality of superposed interspaced horizon-

tally extending ribs disposed between the buttresses and integral with the rear face of the pressure wall and the buttresses, said ribs forming horizontal arches between the buttresses which decrease in span, said spans being longest at the top and decreasing in span towards the bottom of the dam. 35

2. A concrete dam comprising an angularly disposed pressure wall decreasing in thickness from the bottom to the top, a plurality of buttresses on the rear side of the wall, vertically disposed, interspaced and integral with the pressure wall, and a plurality of superposed interspaced horizontally extending ribs disposed between the buttresses and integral with the rear face of the pressure wall and the buttresses, said ribs increasing in depth towards the bottom of the dam, and said ribs also forming horizontal arches between the buttresses. 45 50

3. A concrete dam comprising an angularly disposed pressure wall decreasing in thickness from the bottom to the top, a plurality of buttresses on the rear side of the wall, vertically disposed, interspaced and integral with the pressure wall, and a plurality of horizontally superposed, interspaced ribs disposed between the buttresses and integral with the rear face of the pressure wall and the buttresses, said ribs being disposed at right angles to the rear face of the pressure wall and the outer face of each rib terminating in an arch. 55 60 65
